UNITED STATES PATENT OFFICE.

LEO JOHN BAYER, OF ST. LOUIS, MISSOURI.

SOOT BLOWER FOR BOILERS.

Application filed November 1, 1926. Serial No. 145,690.

My invention has relation to improvements in soot blowers for boilers, and consists in the novel features of construction and more fully set forth in the specification and 5 pointed out in the claims.

The present invention is of the single element type soot blower, that is, it consists of but a single tube through which the steam passes to the orifices adjacent to the boiler tubes, and, also through which air passes 10 to keep the tube comparatively cool when the blower is inoperative.

The adaptation of the blower tube for containing both a steam and an air circulation is of the essence of the invention and makes it possible to dispense with the usual 15 cooling jacket around the blower tube. Other objects of the invention are to provide means actuated by the flow of steam 20 to the blower tube for temporarily shutting off the air circulation; to provide a simple compact construction composed of comparatively few parts; and to provide a device that is durable and will not readily 25 get out of order. Further and other advantages will be better apparent from a detailed description of the invention in connection with the accompanying drawings, in which—

30 Figure 1 is a side elevation of my improved soot blower applied to a boiler, a part of the wall and tubes thereof being shown in section; Figure 2 is an enlarged vertical middle longitudinal section taken 35 along a plane indicated by the line 2—2 on Fig. 3; Fig. 3 is an enlarged vertical cross-section taken on the line 3—3 of Figure 1; and Fig. 4 is a vertical cross-section on the 40 same scale as Figure 1, taken on the line 4—4 of Figure 1.

Referring to the drawings, W represents a boiler side wall, and t, t represent boiler tubes that are to be cleaned by my improved soot blower, which comprises a head H suspended from the wall and a blower tube 1 supported in hangers 2 suspended from the tubes t. An opening O is provided in the wall W into which is inserted a wall-sleeve 3 having a flange 4 to which 45 is bolted or otherwise secured, a bracket plate 5 having an overhanging arm 6. A slot 7 is formed in the arm 6 over which is slid-

ingly fitted a spring seat 8, perforated at 0 to receive a stud 9 projecting upwardly from a standard 10 which forms a part of 55 the head supporting frame 11. A nut 12 is screwed over the upper end of stud 9 between which and the seat 8 is a coiled spring 13 which provides flexibility between the bracket arm 6 and blower head H. An angular hollow casting 14 is bolted to the frame 11, and its horizontal component 15 is adapted to receive the outer end of blower tube 1, and a stuffing box 16, which its vertical component 17, which serves also as 65 a valve casing terminates in a flange 18 whereby it is connected to a steam supply pipe 19.

Within the component 17 of casting 14, about the middle thereof is formed a valve 70 seat 20, below which is a spider 21 the hub of which serves as a guide for stem 22 of valve 23, and above the valve seat is formed a cylindrical guideway 24 for the upper enlarged end 25 of valve 23. The valve 23 is 75 screwed onto the stem 22, which is threaded to provide vertical adjustment, and a lock nut 26 holds the valve in place. The stem 22 extends upwardly through the top wall of casting 14, in which there is a stuffing 80 box 27, and has a head 22' on its upper end between which and gland 27' is a coiled spring 28 which exerts its tension to lift the valve against its seat.

A standard 29 projects upwardly from 85 frame 11 in spaced relation with standard 10, and a shaft 30 is mounted in bearings 31, 32 formed in said standards respectively.

A sheave 33, having a cam 34 projecting inwardly from its hub, is mounted loosely 90 on shaft 30 outside of standard 29 and adjacent thereto, and a sheave 35 is keyed to the outer end of said shaft, said sheaves being traversed by operating chains 36 and 37 respectively which are guided by a bifurcated guide 38 loosely mounted on the outside of the hub of sheave 35. A lug 39 projects outwardly from standard 29 below the cam 34, said lug being perforated to receive a pin 40 bearing against the cam 34 at its 95 upper end and engaged by the head 22' of the valve stem at its lower end. Obviously, on rotating the sheave 33, the cam 34 will 100 operate to depress the pin 40 and valve stem.

22 to unseat the valve 23, and when the low side of said cam comes into contact with pin 40 the spring 28 will force the valve upwardly to its seat. Stops 41, 42 are formed 5 on the sheave 33 which impinge against the lug 39 to limit the rotation of the sheave. When stop 41 is in contact with the lug the valve 23 is closed, and when stop 42 is in contact with the lug the valve is open.

10 The frame 11 is provided with a cage 43 below the standard 10, in which cage is a ball-bearing 44 for the inner end of blower tube 1 which is adapted to be rotated by a gear wheel 45 fixed to the tube adjacent to 15 the ball-bearing, said gear meshing with a pinion 46 keyed on the inner end of shaft 30. The gears 45 and 46 are enclosed in a housing 47 attached by lugs 48 and set screws 49 to the outside of cage 43, said 20 housing having an opening 50 to receive the inwardly projecting boss 10' of standard 10, and an opening 51 to receive the inwardly projecting lug 52 of said standard. The lug 52 serves as a stop for limiting the 25 rotation of gear 45 which has a lug 53 projecting toward lug 52, and as the gear is rotated the lug 53 encounters the lug 52 and arrests rotation of the gear.

Components 15 and 17 of the casting 14 30 are connected by a chamber 54 through which the steam passes to the blower tube 1 when the valve 23 is open. The wall of casting 14 is provided with oppositely disposed threaded openings 55, 55, leading into 35 the chamber 54, and laterally disposed elbows 56, 56 are screwed into these openings. A plurality of lugs 57 project inwardly at the bend of the elbow to support a ball 40 valve 58 the seat 59 for which is formed on the cap 60 screwed into the top of the elbow. The cap has a plurality of air intake ports 61 just below its top wall to which is screwed 45 a cover 62 which overhangs the cap to shield the intake ports 61 from dirt. There is an annular clearance space 63 between the bottom edge of the cover and the cap to permit free entry of air into the elbow 56 and, of course, chamber 54 and blower 50 pipe 1.

At all times that the steam valve 23 is closed air will be entering through the air valves (which the elbow assemblies may be called) and flowing through the casting 14 to the blower tube 1, from which it escapes 55 into the boiler through orifices 64 disposed opposite the boiler tubes. This circulation of air not only serves as a cooling medium to keep down the temperature of the blower pipe, but also assists in the combustion of 60 the furnace gases since it brings to them a fresh supply of highly heated oxygen.

When the steam valve 23 is opened preparatory to blowing the boiler tubes, the steam pressure will instantly lift the ball 65 valves 58 against their seats 59 to shut off

the incoming air and also prevent the escape of steam through the air-valves. The steam then passes into the blower pipe and discharges through orifices 64 against the tubes to blow the soot and ash therefrom.

Having described my invention, I claim:

1. A soot blower for boilers including a head, a rotatable blower tube, and a steam supply pipe for said tube, said head comprising a suitable standard supported from 70 the wall of the boiler, a valve casing suspended by said standard and connecting the tube with the supply pipe, an anti-friction bearing for the tube suspended by the standard, a stuffing-box in the valve casing for 75 supporting and packing the end of the tube, and means for actuating the blower tube.

2. A soot blower for boilers comprising a head and a rotatable blower tube having one end mounted in said head, a valve casing 80 forming a part of said head and communicating with the blower tube, a steam supply pipe connected to said casing, a steam-valve in the casing between the supply pipe and blower tube, an air-intake valve for admitting air to the blower tube, said air valve being arranged to be closed by steam admitted by the steam valve, a rotary cam for actuating the steam-valve, arresting devices for the cam at both the full open and closed 85 positions of the valve, a drive gear for rotating the blower tube, arresting devices for limiting the rotation thereof, and independent means for actuating the rotary cam and the drive gear.

3. A soot blower for boilers comprising a head and a blower tube having one end mounted in said head, a valve casing forming a part of said head and communicating with the blower tube, a steam supply pipe 105 connected to said casing, a steam-valve in the casing between the supply pipe and blower tube, an air-intake valve for admitting air to the blower tube, a protective cover disposed over the air-valve, said cover being 110 spaced from the air-valve to provide a peripheral air intake slot, and means for opening the steam-valve to admit steam to the blower tube, said air valve being arranged to be closed by steam admitted by the steam 115 valve.

4. A soot blower for boilers including a head, a rotatable blower tube, and a steam supply pipe for said tube, said head comprising a suitable standard suspended from 120 the wall of the boiler, a valve casing carried by said standard and connecting the tube with the supply pipe, and separate means carried by said standard for actuating the valve and blower tube.

5. A soot blower for boilers including a head, a rotatable blower tube, and a steam supply pipe for said tube, said head comprising a suitable standard suspended from 125 the wall of the boiler, a valve casing carried 130

by said standard and connecting the tube with the supply pipe, and operating means for the valve and blower pipe, said means comprising a shaft mounted in said standard, an actuating sheave and pinion fixed to the shaft, a gear on the blower tube meshing with said pinion, and an actuating

sheave and cam loosely mounted on said shaft, said cam being arranged to operate the valve.

10 In testimony whereof I hereunto affix my signature.

LEO JOHN BAYER.
